DATING STAMP

George H. Kress, Johnson City, and Myron F. Davis, Jr.,
Binghamton, N. Y., assignors to International Business
Machines Corporation, New York, N. Y., a corpora-
tion of New York

Application April 12, 1955, Serial No. 35,478

Term of patent 14 years

(Cl. D64—11)

FIG. 1

Des. 175,173

PAGE 2

FIG. 2

Fig. 1 is a perspective view of a dating stamp, embodying our design.

Fig. 2 is a rear elevation of the same.

The left side of the stamp is identical to the right side shown in Fig. 1.

We claim:

The ornamental design for a dating stamp, as shown and described.
